UNITED STATES PATENT OFFICE

2,061,530

CONTROL MEANS

Daniel D. Wile, Detroit, Mich., assignor to Detroit Lubricator Company, Detroit, Mich., a corporation of Michigan

Application June 10, 1932, Serial No. 616,539

13 Claims.

(CL 60—52)

My invention relates to new and useful improvements in control means, and more particularly to a device for imparting movement to means to be controlled, such as a lever arm, or the like, which may be operatively connected, for example, to the draft controlling dampers of a heating apparatus.

An object of my invention is to provide a device which is of simple and compact construction, and which will be positive in its operation.

Another object is to provide a device which is operable in response to fluid pressure generated by pumping means.

Another object of my invention is to provide means for relief of the generated pressure.

The invention consists in the improved construction and combination of parts, to be more fully described hereinafter, and the novelty of which will be particularly pointed out and distinctly claimed.

In the accompanying drawings to be taken as a part of this specification, I have fully and clearly illustrated a preferred embodiment of my invention, in which drawings—

Figure 1 is a view in front elevation of a device embodying my invention;

Fig. 2 is a view in section on the line 2—2 of Fig. 1;

Fig. 3 is a view in section on the line 3—3 of Fig. 2, but with the motor removed;

Fig. 4 is a detail view in section on the line 4—4 of Fig. 3, and

Fig. 5 is an enlarged detail bottom plan view of part of the structure of Fig. 4.

Referring to the drawings by characters of reference, 1 designates generally a hollow casing having a substantially horizontal bottom wall 2 with an upward flaring peripheral flange 3 and a central upstanding boss 4. A substantially cylindrical side wall 5 rises from the flange 3 and is clamped and sealed rigidly thereto, as by rolling and solder, or the like, as at 5a. The wall 5 has an inwardly directed annular flange 6 in which is an annular upwardly open recess or groove 7. Seated in the groove 7 and hermetically sealed therein, as by solder, or the like, is the lower open end of a substantially cylindrical, circumferentially corrugated, expansible-collapsible, resilient element 8, such as a metal bellows which forms a portion of the side wall of the casing. The upper end of the bellows 8 is closed and sealed by a movable head 9 which defines the end wall of the casing, and which is preferably provided internally with a reinforcing plate 9a. The flange 6 projects inward beyond the bellows, and

rising from the inner periphery thereof is a hollow cylindrical extension 10 having an end closure wall 11 adjacent the head 9, the wall 11 preferably being provided with radial reinforcing corrugations 12. The extension 10 and wall 11 provide an inverted substantially cup-shaped partition which divides the casing internally into an expansion chamber 13 above and around the partition and a reservoir 14 beneath and within the partition.

A cylindrical container or housing 15 surrounds the chamber 13 and is secured to the wall 5, as at 16, and has a top wall 17 overlying the movable end wall 9. Centrally through the top wall 17 the housing has a plunger receiving aperture 18 and has vent apertures 19 adjacent the wall 5. Projecting upward through aperture 18 is a plunger 20 which is rigidly secured and sealed in an aperture in the wall 9, as at 21, and which has a downward open guide bore 22 receiving a guide pin or rod 23 rigidly and centrally secured to the wall 11, as at 24. The top wall 17 is provided with upstanding spaced bracket arms 25 which are equally spaced and radially offset from the plunger 20 and which are joined by a shaft 26 supported at its ends therein. A saddle member 27 is journaled on shaft 26 and is connected by a pin 28 to the free upper end of plunger 20. The member 27 supports an operating lever arm 29 adjustably secured by a set screw 30 in the aligned apertures 31 of spaced depending flanges 32. The arm 29 is adapted for connection to draft controlling dampers, or the like, and is provided with end apertures 33 to receive damper operating pull chains or rods. A bracket 33a is preferably secured to the housing 15 for mounting the device on any suitable base structure.

Within the reservoir 14 there is a substantially cylindrical housing 34 which fits within the cup-shaped partition, and which rests upon the boss 4. The lower end of the housing 34 has radially extending cross-arms 35 which support a substantially rectangular block member or casting 36 from which an extension 37 projects upward concentrically within the housing. Within the member 36 there is a rotary pump having a pump chamber 38 positioned beneath the extension 37 and from which a cylindrical bore 39 rises vertically through the extension 37. The open under side of chamber 38 is closed by a plate member 40 removably secured to the member 36 by screws 41, or the like, and which directly engages and seats upon the boss 4. Within the chamber 38 there are intermeshing driving and driven pump gears 42, 43. The driving gear 42

42 is keyed, or otherwise secured, as at 44, upon one end of the drive shaft 45 which is journaled in the bore 39. The driven gear 43 is rigid with a stub shaft 46 journaled in an upward extending cylindrical bearing recess in the member 36. The shaft 45 is driven by an electric motor 46' having its armature 47 carried by and fixed on the end of shaft 45 which projects above the extension 37. The armature 47 is preferably recessed, as at 48, to permit the armature to set down over the extension. The field coils 49 of the motor are supported within and by the housing 34. The inlet 50 to the pump chamber is through an aperture in the bottom plate member 15 40. The outlet passage 51 from the pump is preferably a groove or channel in the underface of the block member, and is closed to provide a conduit by the plate member 40. The passage 51 opens into the lower end of a valve chamber 20 52 in the block member. Within the chamber 52 there is a plunger valve 53 controlling an outlet 25 port or passage 54, the valve 53 having a depending boss or abutment 53^a engageable with the member 40 to prevent closing of the passage 51. The outlet passage 54 opens into a valve chamber 30 55 on the inlet side of or beneath a check valve 56, preferably of the ball type, which normally seats by gravity on a valve seat member 57 in chamber 55 to control reverse flow through the port 58 thereof. The chamber 55 above seat member 57 is in communication with a vertical bore 59 which extends through member 36 by means of a passage 60, the bore 59 and chamber 55 being closed at their bottom ends by the plate member 40. Secured and sealed in the bore 59 and extending upward therefrom, is a pipe or tubular member 61 which passes laterally between the motor field coils and projects into chamber 13 through an aperture 62 in which it is sealed in 40 the partition top wall 11. The valve 53 is normally urged downward by a spring 63, preferably of the helical coil type positioned in the chamber 52 and held under compression between the top face of the valve and the top wall of the chamber. A vent 64 is preferably provided in the top wall of chamber 52 to prevent fluid pocketing above the plunger valve. The valve chamber 55 above seat member 57 communicates with chamber 52 by a passage 65. A passage 66 aligned 45 with passage 65 opens from the chamber 52 into the reservoir, flow through the passages 65 and 66 being controlled by the upper end portion of valve 53. A peripheral endless groove or recess 67 in the valve normally communicates with the passages 65 and 66 so as to provide a conduit from the chamber 13 to the reservoir 14 which bypasses the pump.

The motor is connected by electric lead wires, not shown, to the terminal posts 68 within the reservoir, which are insulated from and sealed through the bottom wall 2. The outer ends of the posts 68 are positioned in a conduit box 69 secured to the bottom wall 2 by bolts and cap nuts 70, or the like. The reservoir 14 and chamber 13 are filled with operating fluid, preferably such as oil or other liquid through the plugged and sealed filling opening 71, the oil or other liquid preferably completely filling the chamber and reservoir when the bellows is in neutral or inert position.

The operation of my device is as follows: The motor lead wires are connected at posts 68 to a control switch, which may be thermostatically or otherwise actuated, and the lever arm 29 is connected to some means to be controlled as the

draft controlling dampers of a heating apparatus, or the like, not shown. When the switch controlling the motor 46' is closed to complete the motor circuit, the armature 47 will be rotated and drive the pump gears 42, 43 through the drive shaft 45. The pump will draw liquid from the reservoir 14 through the inlet 50 and discharge the liquid through the conduits 51, 54, 58, 60 and 61 into the chamber 13. The liquid discharged through passage 51 will enter valve chamber 52 beneath the plunger 53, due to the boss 53^a. As the pressure beneath the plunger is built up by the pump, the plunger will be raised against the force of spring 63, and prior to the valve plunger 53 uncovering port 54, the by-pass groove 67 will have passed out of registry with the by-pass conduits 65, 66, and the plunger will have cut off flow therethrough. When the plunger has been raised to uncover port 54, then the liquid entering valve chamber 55 will pass through port 58, raising the check valve 56 and be discharged via passage 60, bore 59 and tube 61 into the chamber 13. The chamber 13 being initially filled with liquid, the additional liquid supplied thereto under pressure by the pump will expand the bellows 8 and move the end wall or head 9 upward to lift the plunger 20. Upward movement of the plunger 20 will act through pin 28 to rock the saddle 21 on its fulcrum 26, raising the right-hand end of lever arm 29 and depressing the left-hand end, facing Fig. 1. When the bellows has reached its limit of expansive movement by abutment with the top wall 17, provided the means actuated by arm 29 has not earlier stopped expansion of the bellows, the pressure in the conduit from the reservoir to the chamber 13 may continue to build up, due to continued operation of the pump. Increased pressure in the conduit and in chamber 52 will act to lift the plunger 53 further against spring 63 until the lower end of the plunger uncovers or lifts above passage 66, and then liquid discharged by the pump in excess of the liquid maintaining the bellows expanded, will flow from chamber 52 through passage 66 back into the reservoir and be circulated by the pump, as long as the motor continues to drive the pump, thus providing a safety means to prevent rupture of the chamber 13, or the liquid conveying passages. When the switch controlling the motor 46 is opened to break the motor circuit, and the pump is stopped, the energy stored in spring 63 by the pressure in excess of that necessary to open port 54, will act to force the oil in chamber 52 back through the pump gears and the inlet 50 into the reservoir. When the pump stops, the check valve 56 will seat and prevent the pressure of the liquid transmitted from chamber 13 by conduit 61 from acting against the underside of plunger 53 in opposition to spring 63. It may be noted that when the plunger 53 is raised to open communication between chamber 52 and passage 66, the chamber 13 will also be in communication with chamber 52 by means of passage 65. The pressure from chamber 13 acting through passage 65 against the underside of the plunger 53, is overcome by spring 63, which need only force a minute quantity of liquid past the pump gears prior to closing off of the passage 65. With the passage 65 closed and the port 58 closed, the spring 63 readily forces the plunger 53 downward to the position of Fig. 4, which opens communication between passages 65 and 66 through the groove 67, which is now in registry therewith. The liquid discharged into chamber 13 by the pump, will now be discharged

from chamber 13 by the resilient force of the bellows 8 acting to return the bellows to neutral inert position, and by atmospheric pressure on the bellows and head 9. The liquid discharged from chamber 13 will be by-passed around the pump chamber and be returned to the reservoir by the conduits 61, 60, 65, 67 and 66, so that the quantity of liquid employed to expand the bellows will pass back freely into the reservoir and the pressure in the chamber 13 will be quickly relieved, which will return the lever arm 29 to the position of Fig. 1, resulting in reversal of operation of the device actuated thereby.

It is to be noted that the force exerted by spring 15 63 in opposition to the plunger 53 is such as to control the by-pass passage 66 and only permit the pressure beneath plunger 53 and in chamber 13 to raise the plunger to open passage 66 when the bellows has been extended its full permitted 20 distance.

What I claim and desire to secure by Letters Patent of the United States is:

1. A device of the character described, comprising a hollow casing, a partition joining the side walls of said casing and dividing said casing internally into an expansion chamber and a reservoir, said chamber having a movable wall, a conduit connecting said reservoir and said chamber, a pump in said conduit to transfer 30 fluid under pressure through said conduit from said reservoir to said chamber to move said wall, an electric motor housed in said reservoir, and a drive shaft connecting said motor and said pump.

2. A device of the character described, comprising a casing having a chamber therein with a movable wall, a reservoir, a conduit communicating with said chamber and with said reservoir, pumping means in said conduit operable to force fluid from said reservoir into said chamber to move said wall, means determining the maximum fluid pressure in said chamber, and means acting automatically upon cessation of operation of said pumping means to relieve said chamber of fluid pressure, said last-named means 45 being operatively connected to and movable with said pressure determining means.

3. A device of the character described, comprising a casing having a partition therein dividing said casing internally into a reservoir and an expansion chamber, said chamber having a movable wall, a conduit communicating with said chamber and with said reservoir, pumping means in said conduit operable to force fluid from said reservoir into said chamber to move said wall, means in said conduit normally acting to prevent flow from said chamber through said pumping means upon cessation of operation of said pumping means, and means operable automatically upon cessation of operation of said pumping 60 means to relieve said chamber of fluid pressure.

4. A device of the character described, comprising a casing having a chamber therein with a movable wall, a reservoir, a conduit communicating with said chamber and with said reservoir, pumping means in said conduit operable to force fluid from said reservoir into said chamber to move said wall, a passageway to return fluid from said chamber to said reservoir, means responsive to predetermined fluid pressure in said conduit to close said passageway, means normally acting to move said responsive means to open said passageway, and means in said conduit between said responsive means and said chamber to close said conduit and prevent transmission of pressure from said chamber to said responsive means 75

upon cessation of operation of said pumping means.

5. A device of the character described, comprising a hollow casing having an inverted substantially cup-shaped partition dividing said casing internally into an expansion chamber and a reservoir, said chamber having a substantially cylindrical expandable-collapsible side wall surrounding said partition and having a movable end wall carried by said side wall, a pump casing in said reservoir, a motor carried by said pump casing and housed in said partition, a pump in said pump casing, means operatively connecting said pump and said motor, an inlet to said pump from said reservoir, and an outlet from said pump discharging into said chamber whereby fluid discharged by said pump will act to move said end wall.

6. A device of the character described, comprising a hollow casing having an inverted substantially cup-shaped partition dividing said casing internally into an expansion chamber and a reservoir, said chamber having a substantially cylindrical expandable-collapsible side wall surrounding said partition and having a movable end wall carried by said side wall, a housing carried by said casing and surrounding said chamber and having an aperture therethrough, a plunger on said end wall and projecting through said aperture, an operating lever operatively connected to said plunger and fulcrumed on said housing, a pump casing in said reservoir, a motor carried by said pump casing and housed in said partition, a pump in said pump casing, means operatively connecting said pump and said motor, an inlet to said pump from said reservoir, and an outlet from said pump discharging into said chamber whereby fluid discharged by said pump will act to move said end wall.

7. A device of the character described, comprising a casing containing an expansion chamber having a movable wall, control means operable by said wall, a reservoir, a conduit connecting said reservoir and said chamber, a pump in said conduit operable to discharge fluid from said reservoir into said chamber, a valve chamber in said conduit between said pump and said expansion chamber, a check valve in said conduit between said chambers, a passage connecting said conduit on the outlet side of said check valve to said valve chamber, a passage connecting said valve chamber to said reservoir, a valve member responsive to fluid pressure and reciprocable in said valve chamber, said member normally closing said conduit and being movable upon operation of said pump to permit flow through said conduit to said expansion chamber, said valve member being movable upon increased fluid pressure to uncover said second-named passage whereby to permit flow from said conduit to said reservoir.

8. A device of the character described, comprising a hollow casing, a partition dividing said casing internally into an expansion chamber and a reservoir, said chamber having a substantially cylindrical expandable-collapsible side wall and having a movable end wall carried by said side wall, a pump casing in said reservoir, a motor in said reservoir and carried by said pump casing, a pump in said pump casing, means operatively connecting said pump and said motor, an inlet to said pump from said reservoir, and an outlet from said pump discharging into said chamber whereby fluid discharged by said pump will act to move said end wall.

9. A device of the character described, comprising a hollow casing, a partition dividing said casing internally into an expansion chamber and a reservoir, said chamber having a substantially cylindrical expansible-collapsible side wall and having a movable end wall carried by said side wall, a pump casing in said reservoir, a motor in said reservoir and carried by said pump casing, a pump in said pump casing, means operatively connecting said pump and said motor, an inlet to said pump from said reservoir, an outlet from said pump discharging into said chamber whereby fluid discharged by said pump will act to move said end wall, a normally open passageway from said chamber to said reservoir operable upon cessation of operation of said pump to relieve said chamber of fluid pressure, and a valve operable upon operation of said pump to close said passageway.
10. A device of the character described, comprising a control means, pressure responsive means for actuating said control means, a conduit for conveying fluid under pressure to said responsive means, pressure generating means connected to said conduit, a normally open passageway for relieving said responsive means of fluid pressure, pressure responsive valve means controlling said conduit and said passageway, said valve means acting upon predetermined generated pressure to close said passageway, said valve means acting upon increase of generated pressure to open said conduit, said valve means acting upon further increase of generated pressure to open said passageway, and means operable upon decrease of generated pressure to close said conduit.
11. A device of the character described, comprising a control means, pressure responsive means for actuating said control means, a conduit for conveying fluid under pressure to said responsive means, pressure generating means connected to said conduit, a normally open passageway for relieving said responsive means of fluid pressure, pressure responsive valve means controlling said conduit and said passageway, said valve means acting upon predetermined generated pressure to close said passageway, said valve means acting upon increase of generated pressure to open said conduit, and said valve means acting upon further increase of generated pressure to open said passageway.
12. A device of the character described, comprising a control means, a casing for containing a reservoir, a metal bellows in said casing and operatively connected to said control means, said bellows defining a wall of an expansion chamber, an electric motor housed in said bellows and having an armature rotatable in a horizontal plane, a vertically positioned rotatable shaft fixed to and supporting said armature, a supporting member for said shaft and projecting upward into said bellows, a rotary pump in said casing operatively connected to said shaft, said pump having an inlet from said reservoir, and an outlet conduit extending from said pump to said expansion chamber.
13. A device of the character described, comprising a hollow casing including a chamber having a movable wall, a movable control means, a hollow stem external of said casing and operatively connecting said wall to said control means, a guide member within and rigid with said casing and extending into said stem to guide said wall, and means to transmit fluid pressure to said chamber.

DANIEL D. WILE.
